ELECTRIC HEATER

Edmond Bryan Williams, Litchfield, Conn., assignor to The Torrington Manufacturing Co., Torrington, Conn., a corporation of Connecticut

Application April 9, 1943, Serial No. 482,473

7 Claims. (Cl. 219—39)

This invention relates to improvements in electric heaters, being particularly applicable to the smaller, portable, hand-held types of electric heaters suitable for use for example, for defrosting purposes in high-altitude aircraft. Some features of the improvements are, however, adapted for heaters of considerably larger sizes whether of stationary, portable or semi-portable types.

The requirements of a small hand-held defroster unit for aircraft, have accentuated the several inadequacies of older, existing portable types of heaters for this usage; this applicant is fully aware of the many designs of smaller portable heater units such as hair dryers and the like, but most of those heretofore available to the trade are inefficient, slow in warming to the desired temperature, needlessly heavy in weight, and difficult of manipulation. It is accordingly a general object of this invention to overcome the difficulties noted with respect to the prevalent types of existing small electric heaters, and objectively to attain a design which is light, easily handled, quick to warm to desired temperature, and offers a minimum resistance to the air stream from the fan, as a result of a novel disposition of the resistance conductors employed for air heating purposes.

Yet another object of the invention is attained in an improved mounting structure or support for an electric heating element such as resistance wire, and which enables the installation of the unit in, or its removal from a fan housing, substantially as a separate unit.

Yet another object is attained in an improved arrangement of insulating elements, means for mounting same, and an improved assembly of resistance wire to such elements for the purposes, first, of minimizing resistance to the fan stream and secondly, of facilitating assembly operations in production of the heater.

Yet another object of the invention is attained in an improved construction of housing for a fan and resistance element in a device of the class referred to, which makes for greater efficiency, quiet operation and efficient delivery of a well confined stream of warm air, as for defrosting purposes.

Yet another object of the invention is attained in certain improved structural features pertaining to the manner of detachably assembling the housing for the fan and heating conductor, to a fan motor, and an improved expedient for providing an assembly of the type noted with a detachable handle or like manipulating member.

Further objects and advantages include an improved construction of housing for the fan and resistance element, particularly a novel arrangement of the inlet portion of the housing; an improved low cost assembly provision through which the housing is supported from the motor, and an improved resistance-mounting spider secured to the housing.

The foregoing and other objectives will more clearly appear from the following detailed description of a preferred embodiment of the device in a hand defroster for aircraft use, particularly when the description is taken with the accompanying drawing, in which:

15 Fig. 1 is a side elevation of a complete hand defroster unit embodying present features;

Fig. 2 is an end elevation as viewed from the front or air delivery end of the unit;

Fig. 3 is a somewhat enlarged vertical sectional elevation through the housing for the fan, and showing the resistance element and its mounting, as taken along line 3—3 of Fig. 2, and

Fig. 4 is a front elevation, in which certain of the elements are shown in section, of the structure of Fig. 3, as viewed along line 4—4 thereof.

Referring now by characters of reference to the drawing, the device comprises as major elements, a small, compact fractional H. P. motor indicated generally at 10. The motor 10 is preferably of an enclosed frame type, requiring no special provisions for ventilation or the like since it usually operates for relatively short periods at a time. Accordingly, the end bell portions 11 at the rear, and 12 at the front, are or may be imperforate. In keeping with standard aircraft practice the motor 10 is of 24 volt D. C. type, and of moderately high speed.

Further major elements include a fan 13, shown as a five-blade sheet metal fan of propeller type, and which is secured as through a hub portion 14 and set screw 15 to shaft 16 of the motor. By preference located somewhat forwardly of the fan 13, is the resistance wire generally indicated at 17 and mounted as hereinafter described.

As a housing structure for the fan and resistance element there is provided a relatively short, tubular, preferably cylindrical sheet metal housing, the body of which is indicated at 20.

50 A pair of end rings or plates are provided as parts of the housing and are designated at 21, being the backplate or ring, and 22, being the plate or end ring at the front or discharge end of the housing. By preference both of the plates 21 and 22 are secured to the end margins of the

body 20 as through crimped joints 23 for the backplate and 24 for the foreplate or ring. Both of the rings 21 and 22 are for obvious reasons profusely perforate for the purpose of offering a minimum of resistance to the flow of air through the housing. This is particularly true and necessary in the case of the foreplate 22 which is of practically completely open aspect, except for a plurality of radial spoke-like portions 25, these being illustrated as six in number. The extent of aperturing of the back plate 21 is of less importance, because of other provisions for supplying intake air to the fan, noted in the present example as a peripheral row of closely adjacent, rectangular inlet openings 26 (Fig. 1). These are arranged as a band of ports adjacent the rearmost margin of the body of housing 20, and are arranged closely to each other, being separated only by relatively narrow bridge portions 27. It will be noted that the band of ports 26 is arranged in substantially the zone of the propeller type fan 13, the center line of the ports lying however slightly to the rear of the median transverse plane through the fan 13. It has been found that the provision of the ports arranged substantially as shown in respect to the fan, results in an efficient and quiet arrangement, and serves to attain, as shown by careful trials, better characteristics of the fan stream delivered by the unit.

Support of the housing 20, the heating element and mounting therefor is conveniently effected, according to the present example, through a plurality of screws 30 extending through a centrally depressed portion 31 in the backplate 21 of the housing, and threadedly engaging suitable tapped screw seats in the end bell 12 of the motor. Since the housing 20 is relatively short, the mounting of the housing to the end bell serves entirely adequately without the provision of any frame members common to the housing and motor other than as described.

Proceeding now to the foreplate or end ring at the discharge end of the housing, this element 22, preferably crimped to body 20 as noted, is characterized by a central imperforate zone 32 from which emanate the arms 25 which extend to and merge into the ring section 33 through which attachment is or may be effected to the end margin of the housing. It may be desired, however, and as shown, to utilize a separate grille element 34 although it will be understood that the grille element may, if desired, be formed integrally with and as a part of the foreplate 22. The grille 34, when utilized, may for example, be formed of quarter inch mesh wire cloth of a good quality, and the grille and foreplate assembled to the housing by a separate crimped band peripherally embracing an upturned flange portion of the housing, the outwardly extending flange portion of the ring or plate 22, and the grille.

As will best appear from Fig. 4 the area of each of the spoke-like portions 25 is kept at a minimum, with the now obvious purpose of minimizing resistance to the fan stream. As the foreplate is punch-formed or otherwise produced, the spoke-like portions or arms 25 are of initially considerably greater area and, except for a minimum sustaining portion, are folded inwardly, i. e., toward the inside of the housing body 20, each at substantially a right angle, thus resulting in inturned flanges 35, it being noted that these are of relatively thin metal, and because of the

bend imparted to each thereof, they are edgewise presented to the air stream from the fan 13.

Secured to each of the flanges 35 is a partly triangular foil or leaf element of a heat-resisting insulating material which, by preference, consists of a relatively thin leaf of mica, this material being preferred because of its unusual heat resistant and high electrical insulating properties. Each of the foils 36 is riveted to one of the flanges 35 as by a pair of rivets 37, and so becomes virtually an extension of the associated flange 35 on each of the arms 25.

As a result of a number of trials of different expedients for mounting the resistance wire 17, and because of the advisability of minimizing the metal fastening expedients for retaining the wire in position, there was evolved the practice of providing each of the mica elements 36 with a deep, open-side recess or notch 40; the foils 36 being so mounted that all of the notches are peripherally presented about the series of mica elements.

It is a preference to employ a nichrome wire as a resistance element, although any suitable equivalent thereof will serve the intended purpose; also, preferably, the wire 17 is closely coiled as will readily appear from Figs. 3 and 4. In installing the wire on the spider constituted by the end ring arms, flanges 35 and associated insulation, the resistance wire is slightly stressed or tensioned as successive arcuate zones thereof are brought around and seated into the successive notches 40 of the arcuate series of mica foils 36. Since, as is usual in aircraft practice, a single wire or grounded leg circuit is employed, the present assembly is or may be so wired; in this case, one end of the resistance conductor 17, as indicated at 41, is grounded to the end plate or ring. The opposite end of the element 17 may be connected, as through a standard aviation single wire connector, indicated generally at 42, and including besides a fillister head screw 43, suitable mica washers 44 or the like, the terminal screw thus being presented as at 45, exteriorly of the lower portion of the housing for the reception of a terminal clamping nut 46 providing a connection to lead wire 47. Actual physical connection between the last mentioned end of the resistance wire, and the terminal assembly 42, is suitably effected by inserting the end of the resistance wire in the slot of the screw head, the slot then being closed by pressure so as firmly and permanently to clamp the end of the resistance wire in place in the screw head.

Further with reference to the spider employed as a unit mounting for, and including the resistance wire, it will appear particularly from Fig. 3 as a preference to impart to the arms 25 and to flanges 35 formed therewith, not only a radial trend but also to locate the center disc portion 32 somewhat to the rear of the plane of the discharge end of housing body 20. The arms 25 and flanges 35 are accordingly given both an inward and a backward direction. This tends to make a more rigid assembly, and to minimize shearing effects on the mica foils as the resistance wire is tensioned thereabout, and results in a rugged and dependable spider mounting and construction. It will have been noted that, although the resistance mounting spider is carried by the extreme end portion of the housing body 20 in the example shown, this construction nevertheless lends itself admirably to assembly in any tubular, particularly cylindrical, air duct employed for electric heating of air in other applications. In

such case, the ring margin of the spider would desirably assume a cylindrical form closely fitting within the inside of a cylindrical housing such as 20.

It is particularly desirable in the case of a small hand held heater for aircraft defrosting purposes, to provide for the handling of the unit with a minimum of effort, and to facilitate the operator's quick service usage of it. Trials with different forms of holders or handles for this purpose have lead to the adoption of a pistol grip type of handle, indicated generally at 50, which is of a rounded, palm-fitting contouring, as shown by Figs. 1 and 2, laterally milled if desired, and provided on its upper surface nearest the frame 10 of the motor, with a dished motor-frame-receiving seat 51, into which is snugly saddled the central portion of the motor frame 10, the handle structure being further shouldered if desired as at 52 to obviate any tendency to fore-and-aft rocking displacement of the motor on the handle. Assembly securement of the motor, and hence of the remaining operative elements of the structure and the housing, is conveniently effected through a contractile band, of tempered spring steel for example, indicated at 53, the opposite ends of which are apertured so as laterally to engage the pistol grip handle 50, and being secured thereto under tension as through a pair of screws or a through bolt 54.

As a convenience for the hanging support of the unit in a position for ready access, there is provided a top loop element 55. This may be formed of a separate metal element embracing the top portion of the band 53, but if desired may, as shown, consist of upwardly extending apertured ear portions 56 provided with a hook receiving opening 57.

It is a preference, in order to facilitate on-and-off control of the unit, to provide in an easily accessible position, say for the forefinger of the operator's hand, a trigger type or toggle type control switch, the actuating element of which is indicated at 60, and which is preferably so arranged in circuit as to control the energization concurrently, of both the motor 10 and the resistance unit 17. The switch proper (the mechanism of which is not shown since it forms per se no part of the present invention) may be recessed in a suitable socket within the handle 50, and the circuit leads 61 and 62 brought out at a convenient zone in the lower portion of the pistol grip.

The function and usage of the portable defroster described, is thought to have been fully apparent from the description of parts and their functional relation. It may however for completeness be noted that, incident to a period of use the unit is gripped as by handle 50, removed from support by withdrawing the hook-engaging eye element formed of parts 56 from their support, switch member 60 being moved to circuit closing position by the forefinger of the gripping hand. This movement of switch arm 60 serves to start the motor and to energize, with a quick heating effect, the resisting element 17. The air supplying the fan 18 is taken in some degree through the back plate 21 to the extent that the latter is apertured, but in important measure also through the row of ports 28, and is thence directed forcibly from that portion of the fan having the highest linear speed and greatest air delivery characteristics, directly across the resistance element 17 for heating purposes.

It will now have appeared that the invention embodied in the form herein described, serves

fully to attain each of the several objects above specifically set forth, and others implied from the description of parts and their function.

Although the invention has been described by making detailed reference to a specific embodiment, the detail of description is to be understood solely in an instructive, and not in any limiting sense, since many changes are possible within the scope of the claims hereunto appended.

10. I claim as my invention:

1. In a portable electric heating device, a motor, a fan driven thereby, a resistance element in the fan stream, a tubular housing of sheet material about the fan and resistance element, the fan being located in one end portion of the housing and the resistance element nearer the opposite end thereof, the housing being provided with a peripheral row of closely spaced, axially elongate, primary air inlet apertures arranged as a band near the inlet end of the housing and in a zone about the fan, the remainder of the housing body beyond said row of apertures, being imperforate, except for end openings to permit the passage of air therethrough, and an end plate secured to the discharge end of the housing body and provided with a plurality of spoke-like, inwardly projecting flanges, the resistance element being carried by and in insulated relation to said flanges.

20. 2. In a portable electric heater adapted for use as a defroster or the like, a motor, a fan driven by the motor, a resistance element located forwardly of the fan and a housing for enclosing the fan and resistance element, the housing including a substantially cylindrical body and a pair of end rings each in the nature of a plate sufficiently apertured to pass a current of air through the housing, the housing being provided with a perimetral row of air inlet apertures of rectangular form, the apertures being located close to each other in the row, being elongate in a direction axially of the housing, and at least partly overlying the fan periphery, the end rings being crimped into securement with the end margins of the housing body, a grille element disposed between the outermost end ring and the housing body and assembled through crimping of the adjacent end ring thereto, the last said end ring 35 including a plurality of spoke-like elements each of substantially planar aspect and with its planar portion directed inwardly of the housing in the form of a flange presented edgewise to the fan stream, a resistance element, and means by which the resistance element is supported in insulated relation from said flange portions.

30. 3. In an assembly for the purpose noted, an electric motor, a fan, a resistance element, a housing for the fan and resistance element carried by one end of the motor, a contractile band embracing the motor frame, a handle of pistol-grip type, the contractile band being detachably secured to the handle, the handle bearing an acute-angled relation to the motor frame and housing and having a hollow extension forwardly and upwardly of its grip portion, a switch mechanism in the hollow-extension, and a switch actuating member projecting forwardly of the extension in a position to be actuated by the forefinger of the gripping hand of the user.

40. 4. In an electric heater housing for conducting a stream of air while same is being heated, a tubular sheet metal body through which the stream of air is to be conducted, a plate element securely crimped into reinforcing attachment with one

end of said body and being in the form of a ring provided with a plurality of substantially radial arms, also extended axially inwardly of the tubular body, a foil of sheet insulating material carried by each of said arms and projecting inwardly from the end of the housing and edgewise to the stream of air passing therethrough, each of said foils being provided with a notch in one of its margins, and a length of resistance wire, for heating purposes, seated in said notches.

5. The combination and arrangement of parts as set forth in claim 4, but further characterized in that the resistance wire is seated in tensioned relation in the several notches of the insulating elements and is arranged in arcuate form substantially in a plane transverse to the direction of air flow through the housing.

6. In an electric heater assembly of the general type described, a motor, a fan, a resistance element, a housing about the fan and resistance element, a plate across one end of the housing and being of substantially open construction inwardly of its periphery, the end plate being secured along its periphery to the discharge end of the housing, and including a plurality of substantially radial flanges extending from its peripheral portion inwardly substantially to the center of the plate, the flanges collectively being dished inwardly of the discharge end of the housing, and each having a trend depthwise as well as radially

of the housing, and thin, foil-like insulating extensions on the several flanges, edgewise presented to the fan discharge stream and provided with open notches in which the resistance element is seated, whereby the flanges and extensions constitute a support for the resistance wire and a reinforcing end frame for the housing.

7. A ring support for a length of resistance wire or the like, as in an electric heater, a tubular enclosure for the ring support, the support being formed up as a spider having a closed continuous periphery adapted for mounting securement to the enclosure, the spider consisting of a plurality of flanges each of a relatively thin substantially planar aspect and each directed both radially inwardly of the spider, and axially inwardly from the plane of the periphery of the spider, a foil of mica secured to each of said flanges, each foil provided in its radially outermost portion with a deep recess or notch, and a length of closely coiled resistance wire having spaced turns thereof seated in said recess whereby the resistance wire embraces the notched edges of the foils under an appreciable tension, means for mounting the spider, means for impelling a current of air across the turns of resistance wire and edgewise along the mica foils, thence out of the tubular enclosure, and means for supplying current to the resistance wire.

EDMOND BRYAN WILLIAMS. 30
